UNITED STATES PATENT OFFICE.

HENRY FREDERICK W. DORNETTE AND JOHN HENRY F. DORNETTE, OF CINCINNATI, OHIO.

DESK FOR TYPE-WRITING MACHINES.

SPECIFICATION forming part of Letters Patent No. 622,211, dated April 4, 1899.

Application filed November 22, 1897. Serial No. 659,393. (No model.)

To all whom it may concern:

Be it known that we, HENRY FREDERICK W. DORNETTE and JOHN HENRY F. DORNETTE, citizens of the United States, and residents of the city of Cincinnati, in the county of Hamilton and State of Ohio, have invented certain new and useful Improvements in Desks for Type-Writing Machines, of which the following is a specification.

10 The several features of our invention and the various advantages resulting from their use, conjointly or otherwise, will be apparent from the following description and claims.

In the accompanying drawings, making a part of this specification, and in which similar letters of reference indicate corresponding parts, Figure 1 represents a view in perspective of a type-writer and desk combined with our invention and constructed according to the latter. Fig. 2 is a sectional view of the same (without the type-writer machine) when the desk is closed and the type-writer is hidden from view. This section is taken in a vertical plane passing through the desk, 25 at the middle of the length of the latter, from front to rear. That side of the section is presented which faces toward the left in Fig. 1. Fig. 3 is a sectional view similar to that of Fig. 2, but showing the mechanism in the 30 position it assumes when the desk is open and the type-writing machine is presented ready for use. Fig. 4 represents a vertical cross-section of the central portion of the machine, taken in the plane of the dotted line 35 44 of Fig. 2, that face of the section being presented which faces toward the left in said Fig. 2. Fig. 5 represents a detail of a sliding shelf for holding the type-writing machine and capable of being slid forward and backward on the supporting-platform.

A indicates the desk, consisting in regard to its general conformation of a central portion B and two supporting sides C C. The sides C may be utilized in any desired manner. In the present illustrative instance the sides are provided with compartments D, containing drawers D². The lower front part of the central portion B is preferably provided with a space to receive the knees and feet of the type-writer operator. At the rear of this

space the inclined partition E is present, connected at its side edges to the sides C and at its top edge preferably united to a cross-bar E². Each side C is covered at C² with a suitable tabular top, and the rear portion of the central compartment B is covered with a tabular top C³, and we prefer to make the latter in one with the table-tops of the sides. The space above the horizontal plane passing through the bar E² and bounded by the sides C and the rear table-top C³ is constructed to receive the type-writing machine W as it rises into the position to be used.

The platform F is the one on which the type-writing machine is to be located. This platform moves up and down in an inclined direction, but always remains horizontal. It is preferably provided at its rear with a guard-piece F². Against the latter the rear of the base of the type-writing machine can impinge. In any event this guard prevents the machine W from slipping or being moved rearward beyond the platform F. The platform F is also provided with side guards F³ F³. The platform F preferably does not occupy the entire horizontal space from side to side of compartment B. In such event there will usually be present stationary edgings T T². Beneath the platform F and inflexibly fixed thereto, so as to move as one with it, there is a guiding device F⁴, which slides on or within guides G, inclined downward and rearward, as shown, and affixed in a stationary manner to the frame of the desk. In the present illustrative instance the guiding device is in one piece and extends across compartment B. Each side edge of this guiding device F⁴ enters a channel G² of the guiding device G on the adjacent side and is slidable therein. So far as the mechanism thus far described is concerned the platform F, with its guiding-plate F⁴, is free to slide from the horizontal plane of the bar E downward and rearward until the plate F⁴ reaches the lower terminus of the guideways G G, and it is then free to be moved upward and forward to the first-named position. For thus lowering and raising the platform F we employ a combination of levers and connecting-rods of our invention. To secure uniformity of construc- 100

tion and ease of movement and to prevent all binding of the operating parts and of the sliding mechanism F⁴ G, we duplicate the combination. For economy of cost and of space and to utilize further the cover we make it an element in the said combination. This combination is as follows: To the platform F, preferably to the outer side of the guard F³ thereof, we pivotally connect at H² 5 a short connecting-rod H. To the other end of this rod H—viz., at H³—we pivotally connect one end of a lever J, whose other end is pivotally connected at J² to a stationary portion of the frame. To this lever J there is 10 pivotally connected at K² one end of a connecting-rod K, whose other end is pivotally connected at M² to a bent lever pivotally fulcrumed (on a stationary fulcrum) to the frame at M³. The other end of this bent lever is 15 pivotally connected at N² to the adjacent corner of the rear end of the cover N. The cover N at its adjacent front corner—viz., at P²—is pivotally connected to one end of a drop-flap N³, and the other end of the latter is pivotally connected at P³ to the frame. The drop-flap is hinged to the cover at P⁴. As before noted, one such combination of levers and connecting-rods is present at the right-hand side of the platform and of the cover and 20 another such combination at the left-hand side of the same.

The operation of the parts thus described is as follows: When the respective parts of the mechanism occupy the position shown in 35 Fig. 2, the platform F occupies its lowest position and the type-writing machine thereon is concealed from view, and the desk, so far as said machine is concerned, is closed, and the cover N being in place protects the 40 machine from dust and injury. Whenever the operator desires to use the type-writing machine, he lifts the front edge of the cover N and carries it up and over in the arc of a circle, permitted and regulated by the connecting-rod P, until the cover assumes the 45 position shown in Fig. 3. A stop S of the frame limits descent of the cover below the desired point. During this movement of the cover the end at N² of the lever M has been forced 50 down and its other end at M² has been forced forward and the connecting-rod K moved forward, and the latter has moved the free end (at H³) of lever J upward, and the latter, in turn, has moved the connecting-rod 55 H forward, and thus moved the platform upward, and the latter, guided by its guides, has moved forward and upward to the horizontal plane of the upper edge of the bar E² and has carried the type-writing machine to 60 the position shown in Fig. 1 and conveniently ready for use. This upward and forward movement of the platform and the upward and forward movement of the free end of lever J has caused the lever J and the rod H 65 to aline after the manner of a toggle-joint when straightened. These levers J and rod H being in the same vertical straight line will

carry any weight up to that required to crush them or break their pivots. They are therefore when made of a moderate size capable 70 of well sustaining the weight of the type-writing machine. Being in vertical alinement, the weight of the type-writing machine and the platform and of those parts of the mechanism which they sustain has no tendency to deflect them. Thus the machine remains locked in this position. Furthermore, the position and weight of the cover N tend 75 to lock the mechanism in place for upholding the platform and keeping it immovable. 80 When it is desired to lower the type-writer and close the desk, the operator takes hold of the upper (front) edge of the cover and draws the cover upward. Such a movement forces the free end (at H²) of lever J backward and downward, moving the lever J out of alinement with rod H, and draws upon this 85 rod H. As the operator continues to draw the cover upward and forward, as permitted to do by the rod P, the platform and the type-writing machine upon it descend until they 90 reach the position shown in Fig. 2. By this time the cover has been closed down and the type-writer is again protected from accidental 95 injury and from dust. In order to conveniently close the gap between the bar E² and front edge of the cover N, a drop-flap N³ is provided, suitably hinged, in connection with the cover, as aforementioned. When the cover is closed, the flap is down and covers this opening between the cover and bar E². As the cover is thrown back the flap N³ lies back and against the cover, as shown in 100 Fig. 3, and is thus out of possible interference with the type-writing machine. 105

Among the various advantages which belong to our invention are the following: The platform is on a level at all times. It never tilts. The type-writing machine therefore is always in its normal position, having the bottom horizontal, and is never tilted. Again, neither the platform nor the type-writing machine thereon need to be lifted when the lid is lifted to lower the platform and its load. When the platform is at its uppermost position, it is not only locked, so that it will not accidentally descend, but it is capable of carrying a very heavy amount of load in addition to the weight of the type-writing machine. The primary reason for this last-named advantage lies in the arrangement of the parts J and H. 115

Another advantage is that no extra weights are needed to counterbalance the weight of the platform and the type-writing machine 120 thereon. The parts as constructed constitute without extra weights a proper counterbalance for one another. The platform and its load can be moved up and down with great facility. 125

It may at times be desirable to bring the type-writing machine forward, so as the better to reach and operate it. In such event suitable mechanism for this purpose is to be 130

employed. One convenient and simple kind of such mechanism is as follows: The platform is provided with two guideways W^3 , affixed to the top of the platform. The edges 5 of a sliding plate W^2 or the like fit into the guideways of these guides, while the plate itself may rest on the platform. On the sliding plate W^2 is located the type-writing machine. By drawing the plate W^2 forward the 10 machine may be advanced toward the operator. When the desk is to be closed down, the plate W^2 and the machine are moved back altogether upon and over the platform.

What we claim as new and of our invention, and desire to secure by Letters Patent, 15 is—

1. In a type-writing desk, the combination of a cover and a movable platform F , short rod H whose upper end is attached to this 20 platform F , and lever J , pivotally fulcrumed at its lower end J^2 to a fixed portion of the desk, and at its upper end pivoted to the lower end of the rod H , and link K , whose lower end is pivotally connected to lever J 25 near the latter's mid-length, and lever M , curved for one end portion, and pivotally fulcrumed at M^3 in the neighborhood of said curve, to a fixed part of the desk, and connected at its lower end at M^2 to the upper end 30 of link K , and at its upper end pivotally connected at N^2 to the rear end of the cover, and guides adapted to obliquely guide the platform up and down, and means for oscillating the cover, substantially as and for the 35 purposes specified.

2. In a type-writing desk, the combination of a cover and a movable platform F , short rod H whose upper end is attached to this 40 platform F , and lever J , pivotally fulcrumed at its lower end J^2 to a fixed portion of the desk, and at its upper end pivoted to the lower end of the rod H , and link K , whose lower end is pivotally connected to lever J near the latter's mid-length, and lever M , curved for 45 one end portion, and pivotally fulcrumed at M^3 in the neighborhood of said curve, to a fixed part of the desk, and connected at its lower end at M^2 to the upper end of link K , and at its upper end pivotally connected at 50 N^2 to the rear end of the cover, and guides adapted to obliquely guide the platform up

and down, and the cover N and link P , one end of the latter being pivoted at P^2 to the forward end of the cover, the other end of this link P being pivoted at P^3 , under the 55 cover, and near the mid-length of the latter, to a fixed part of the desk, substantially as and for the purposes specified.

3. The combination of a type-writer desk, the cover, the curved lever connected to said 60 cover, the type-writer table, a toggle-joint connected to said table and to the desk, and connections between said lever and one of the arms of the toggle-joint, whereby the upsetting of the cover raises the table by means of 65 the toggle-joint, the parts being so arranged that the arms of the toggle-joint are in vertical alinement at the end of movement, whereby the type-writer table is solidly supported, substantially as described. 70

4. The combination of a type-writer desk, the cover, the type-writer table, the toggle-joint, one end of which is connected to the type-writer table and the other to the desk, and connections between said cover and one 75 of the arms of the toggle-joint, whereby the upsetting of the cover raises the type-writer table and causes the toggle-lever to straighten out so that at the end of the movement the type-writer table will be directly supported 80 by the links of the toggle-joint which are then in vertical alinement, substantially as described.

5. In a type-writing desk, the combination of the platform, reciprocable in oblique guideways, and the toggle-joint H , J , and bent lever M and connecting-rod interconnecting lever J and lever M , and the cover pivoted to lever connected to lever M , and adapted to move up and over the platform, as the platform is lowered, and vice versa, when the latter is raised, these devices being arranged as described for enabling the movement of the cover to put the members of the toggle-joint in alinement when the type-writing floor is 95 elevated substantially as and for the purposes specified.

HENRY FREDERICK W. DORNETTE.
